UNITED STATES PATENT OFFICE.

JAMES A. FULLER, OF PROVIDENCE, RHODE ISLAND, ASSIGNEE TO HAMILTON & HAMILTON, JR., OF PROVIDENCE, RHODE ISLAND.

NECKTIE-FASTENER.

1,143,580.

Specification of Letters Patent. Patented June 15, 1915.

Application filed November 3, 1914. Serial No. 370,147.

To all whom it may concern:

Be it known that I, JAMES A. FULLER, a citizen of the United States, residing at Providence, in the county of Providence and State of Rhode Island, have invented a new and useful Improvement in Necktie-Fasteners, of which the following is a specification.

This invention relates to certain new and useful improvements in necktie fasteners, and the primary object of the invention is to provide a fastener of the type set forth embodying an ornamental pin which penetrates the necktie so as to hold same in position and which also serves as an article of 15 jewelry.

A further object of the invention is to provide a necktie fastener which embodies a clasp which latter has the pin secured thereto, so that the clasp acts as an anchor for 20 the pin and the pin acts to prevent loss of the clasp, in event of the latter having its jaws disengaged from the shirt.

In the drawings—Figure 1 is a front elevation of the invention as in use. Fig. 2 is 25 a top plan view of the invention. Fig. 3 is a section on the line 3—3 of Fig. 2. Fig. 4 is an enlarged section on the line 4—4 of Fig. 3, and Fig. 5 is a view similar to Fig. 3, showing the lock for the pin in open position.

The clasp 1 may be of any desired construction, and one of the jaws thereof is provided with an open-ended sleeve or socket 2 slotted at 3. The ornamental pin 35 has a head 4 and a shank 5 which latter is circularly grooved at 6. When the pin is in normal position it occupies the position shown in Fig. 4, in which its inward movement is restricted by engagement with the 40 other of the clasp jaws, and when in the aforementioned position, the groove 6 registers with the slot 3 of the sleeve 2. A locking member 7 is pivoted at 8 and is receivable within the slot 3 and also in the groove 45 6 of the pin shank 5 so that when so engaged with the pin shank, the latter will be locked against outward movement, as is apparent from Fig. 4 of the drawings.

For the purpose of moving the locking member into and out of locking position, a cam member 9 is employed which is pivoted at 50 10 and has a cam edge 11 which moves the member 7 into locking position and a finger 12 which moves the member 7 out of 55 locking position as will be apparent from

inspection of Figs. 3 and 5 of the drawings. The handle of the cam member 9 projects out from the space between the two jaws of the clasp so as to be easily operated.

In operation the clasp is first secured to 60 the shirt and the necktie is placed over the clasp, following which the pin is passed through the necktie and into the socket or sleeve 2, the handle of the cam member having been previously moved to the position 65 depicted in Fig. 5, so as to move the locking member 7 to inoperative or unlocked position. As soon as the pin has been placed in the socket 2, the handle of the cam member 9 is then moved to the position illustrated in 70 Fig. 3 in which position the cam 11 will rock the member 7 so as to move the latter into locking position, in which position, member 7 is moved into the slot 3 and in the circular groove 6 of the pin shank. 75

It will thus be apparent that even should the clasp jaws be pulled away from the shirt, the clasp will still be supported by the pin, thereby preventing possible loss of the clasp, and the clasp in turn acts as an anchor 80 for the pin while still allowing the latter to be displayed in connection with the necktie.

The device thus serves not only as a loss preventing means for the pin of the necktie, but also serves by reason of the presence 85 of the clasp to hold the necktie against lateral movement.

Having thus described my invention, I claim as new and desire to secure by Letters Patent;—

1. In combination with a member having an open-ended socket with a transverse slot therein, a pin having a groove formed in its shank for registry with the slot of the socket, a locking member pivoted to said member and engageable in the slot and in the groove to lock the pin, and a cam member pivoted to said member for actuating the locking member, said cam member having a cam edge to force the locking member 100 to locking position, and having a finger to engage the locking member to move the latter to unlocked position.

2. In combination with a socketed element and a pin receivable in the socket thereof, said pin having a groove, a pivoted locking member on the element receivable in the groove, and a pivoted cam member for moving the first member to locking position, said cam member having means to move the first 110

member out of locking position when the cam member is moved in one direction.

3. In combination with a supporting element and a pin engageable therewith, a pivoted member engageable with the pin to lock the latter to the element, and pivoted means inter-engaged with said member in all movements of the latter for moving the member into and out of engagement with the pin.

4. In combination with a supporting element and a pin engageable therewith, a pivoted member engageable with the pin to lock the latter to the element, and pivoted means having a cam to engage the member to move the latter into locking engagement with the pin when said means is moved in one direction and having a finger engageable with

the member to move the latter out of locking position when said means is moved in the opposite direction.

5. In combination with a supporting element and a pin engageable therewith, means to lock the pin to the element, and pivoted means interengaged with the locking means in all movements of the latter to actuate the locking means into and out of locking positions.

In testimony whereof I have signed my name to this specification in the presence of two subscribing witnesses.

JAMES A. FULLER.
